DESIGN FOR A LOCKET BROOCH OR SIMILAR ARTICLE

Joseph Manuel de Aragon, New York, N. Y.

Application March 2, 1943, Serial No. 109,686

Term of patent 7 years

To all whom it may concern:

Be it known that I, Joseph Manuel de Aragon, a citizen of the United States, residing at No. 548 West 188th Street, in the city of New York, in the county of New York and the State of New York, have invented a new, original, and ornamental Design for a Locket Brooch or Similar Article, of which the following is a specification, reference being had to the accompanying drawing, forming part thereof.

Fig. 1 is a front view of a locket brooch showing my new design;

Fig. 2 is a top view of the globe portion thereof, the V-portion and chain having been omitted, and

Fig. 3 is a view of the globe portion in an open position, the V-portion and part of the chain having been omitted.

I claim:

The ornamental design for a locket brooch or similar article as shown.

JOSEPH MANUEL DE ARAGON.
